SWITCH CONSTRUCTION

John J. Kojis, Chicago, Ill., assignor to S & C
Electric Company, Chicago, Ill., a corporation
of Delaware

Application June 28, 1950, Serial No. 170,858

9 Claims. (Cl. 200—146)

1

This invention relates, generally, to load interrupter disconnecting switches, and it has particular relation to such switches in which a load interrupter device is removable and replaceable as a unit while the switch is energized. The construction herein disclosed is an improvement over that disclosed in the copending application of Lindell, Serial No. 3,221, filed January 20, 1948, and assigned to the assignee of this application. The present invention is usable in conjunction with the switch construction shown in Lindell et al. Patent No. 2,351,826, issued June 20, 1944.

Among the objects of this invention are: To provide for safely, simply, and efficiently removing a load interrupter device from and replacing it in operative position on an energized switch contact for inspection and maintenance; to hold the load interrupter device temporarily in plugged in position and to clamp it securely in operative position by using a live line tool; to employ a pair of studs projecting from the switch contact into a pair of openings in a contact plate forming a part of the load interrupter device for effecting this temporary retention; to clamp the load interrupter device in operative position by a bolt loosely carried thereby and threadable by a live line tool into a tapped opening in a contact plate carried by the switch contact; to employ a socket for receiving a plug forming a part of the load interrupter device and to position the former to receive the latter between a pair of spaced apart switch blade members that are movable as a unit; to manipulate the clamp bolt from a remote point by a live line tool extending through the space between the switch blade members; and to attach a live line tool to the load interrupter device by a threaded connection to permit manipulation thereof from a remote location.

Other objects of this invention will, in part, be obvious and in part appear hereinafter.

This invention is disclosed in the embodiment thereof shown in the accompanying drawings and it comprises the features of construction, combination of elements and arrangement of parts which will be exemplified by the construction hereinafter set forth and the scope of the application of which will be indicated in the appended claims.

For a more complete understanding of the nature and scope of this invention, reference can be had to the following detailed description, taken together with the accompanying drawings, in which:

Figure 1 is a view, in side elevation, of a load interrupter switch construction in which the present invention is embodied;

2

Figure 2 is a view, in front elevation, taken generally along the line 2—2 of Figure 1 and showing the upper portion of the switch construction including the load interrupter device;

5 Figure 3 is a view, at an enlarged scale, partly in side elevation and partly in section, of the socket member which forms an integral part of the energized switch contact;

Figure 4 is an elevational view taken along the 10 line 4—4 of Figure 3;

Figure 5 is a view, partly in side elevation and partly in section, of the plug in terminal portion of the load interrupter device which is arranged to detachably interfit with the socket member 15 shown in Figure 3; and

Figure 6 is an elevational view taken generally along the line 6—6 of Figure 5.

Referring now particularly to Figure 1 of the drawings, it will be observed that the reference 20 character 10 designates, generally, a load interrupter type of disconnecting switch. The switch 10 includes a channel iron base 11 which carries upper and lower stationary insulators 12 and 13. They are spaced from the channel base 11 by spacers 14 so as to be aligned generally with a rotatable insulator 15 which is secured to a shaft 16 that is rotatably mounted in a bearing construction 17 carried by the base 11 near its lower end. An operating arm 18 is clamped to the shaft 16 for connection to a suitable remote operating mechanism. It will be understood that the switch 10 can be mounted for gang operation with one or two other similar switches as may be required.

35 The lower stationary insulator 13 carries a stationary hinge member 21 on which a switch blade, shown generally at 22, is rotatably mounted by a shaft 23. The switch blade 22 has a bracket 24 attached thereto to which a rod 25 is secured by a universal joint for operating the switch blade 22. At its lower end the rod 25 is rockably mounted on the outer end of a crank arm 26 which is fast on a shaft 27 that is carried by and is rotatable with the rotatable insulator 15.

40 45 The hinge member 21 has an extension 28 formed integrally therewith and its lower end portion is guided on the shaft 27. At its lower end the extension 28 has a terminal pad 29 to permit electrical connection thereto.

50 As illustrated more clearly in Figure 2 of the drawings, the switch blade 22 comprises switch blade members 32 and 33 that are spaced apart while their upper ends 34 are positioned in closer spaced relation to engage the opposite sides of a normally energizable switch contact 35. The switch contact 35 has a terminal pad 36 formed

55

integrally therewith to permit electrical connection thereto. A bolt 37 extends through the upper ends 34 of the switch blade members 32 and 33 and functions in conjunction with spring means to provide the desired contact pressure with the sides of the switch contact 35.

Removably mounted between the switch blade members 32 and 33 is a load interrupter device that is indicated, generally, at 40. The details of construction of the load interrupter device may be those described in Lindell et al. United States Patent No. 2,351,826, issued June 20, 1944. It will be understood, however, that other types of load interrupter devices can be employed if desired. In the construction shown in this patent the load interrupter device is not intended to be removed from the switch contact on which it is mounted while this contact is energized. Rather, it is necessary to deenergize the circuit before any work can be done on the load interrupter device by way of repairing or replacing it. In accordance with the present invention provision is made for removing the load interrupter device 40 while the switch contact 35 on which it is mounted is energized.

With this object in mind the load interrupter device 40 is arranged to be plugged into a cylindrical opening 41 in a socket member 42, Figures 3 and 4, which is formed integrally with a flange 43 that, in turn, is formed integrally with the switch contact 35. Flush with the front side of the socket member 42 is a contact plate 44 that also is formed integrally with the associated parts.

In order to cool and condense the gases that are evolved on opening of the circuit by the load interrupter device 40, a screen 41' of copper wire is located within the opening 41. Ports or vents 42' are provided in the surface of the contact plate 44 to relieve to the atmosphere the pressure built up in the socket member 42.

The load interrupter device 40 includes a cylindrical insulator 45 having a terminal housing 46 at its outer end. The housing 46 not only serves to enclose a portion of the operating mechanism of the load interrupter device 40 but also, as the name implies, functions as one terminal thereof. At the other end of the cylindrical insulator 45, Figure 5, is a terminal 47. Integrally formed therewith is a plug 48 that is arranged to interfit with the cylindrical opening 41 in the socket member 42. Formed integrally with the terminal 47 is a contact plate 49 that is arranged to cooperate flatwise with the contact plate 44 when the plug 48 of the load interrupter device 40 is inserted in the cylindrical opening 41.

The load interrupter device 40 is provided with a closing arm 50 on one side and an opening arm 51 on the other side. These are shown in Figures 1 and 2. The switch blade member 32 carries a closing detent 52 and the switch blade member 33 carries an opening detent 53. It will be understood that, when the switch blade 22 is swung from the closed position shown in Figure 1 toward the open position, the opening detent 53 engages the opening arm 51 and moves it to operate the load interrupter device 40 and open the circuit therein. On the reverse movement of the switch blade 22, the closing detent 52 engages the closing arm 50 and operates the load interrupter device 40 from the open to the closed circuit position. The closing detent 52 is elongated, as shown in Figure 1, in order to permit operation of the load interrupter device

40 as long as it remains in the plugged in position only by movement of the switch blade 22 toward the open circuit position.

Normally the terminal housing 46 is disconnected from the circuit, except through the load interrupter device 40, when the switch blade 22 is in the closed position as shown in Figure 1. Prior to disengagement of the switch blade 22 from the normally energizable switch contact 35, a parallel circuit is completed through the load interrupter device 40. For this purpose projections 54, constructed as disclosed in Kojis application Serial No. 158,246, filed April 26, 1950, and assigned to the assignee of this application are provided on the underside of the terminal housing 46. A bow contact 55 is positioned between the switch blade members 32 and 33 and is arranged to engage the projections 54 for completing the circuit through the load interrupter device 40 during a portion of the opening and closing movement of the switch blade 22.

It is desirable to hold the load interrupter device 40 temporarily in the plugged in position in order to permit manipulation of the clamping means to be described. For this purpose longitudinally slotted hollow pins 56, Figures 3 and 4, are threaded into the contact plate 44 and project a substantial distance beyond the surface thereof. The pins 56 are arranged to interfit with openings 57, Figures 5 and 6, in the contact plate 49. These openings 57 have flared-out portions 58 for guiding the rounded heads of the pins 56 into the openings 57. Rubber inserts 56' are positioned in the openings in the pins 56 to prevent entrance of dirt, etc., and to increase the force acting to flex the slotted portions outwardly. The rear portions 59 of the rounded heads of the pins 56 are rounded to cooperate with a chamfered surface 60 at the forward ends 40 of the openings 57 to squeeze the slotted portions inwardly when the load interrupter device 40 is withdrawn. Not only do the pins 56 serve to hold the load interrupter device 40 temporarily in position in the socket member 42 by the reaction between the rear portions 59 of the pins 56 and the chamfered surfaces 60 of the openings 57, but also they provide for automatically aligning it the proper position.

It is desirable that the load interrupter device 40 be securely clamped to the contact plate 44 not only to provide the desired electrical connection therewith but also to resist the mechanical stresses which are incident to the operation of the load interrupter device 40 by the switch blade 22 as it is moved out of or into the closed position. For this purpose clamping means in the form of a captive bolt 61 is employed. As shown more clearly in Figure 5 the bolt 61 has a reduced central portion 62 so that it is loosely fitted in a threaded opening 63 in the contact plate 49. At its inner end the bolt 61 has a threaded portion 64, this thread being the same as the thread in the opening 63 which, while permitting the bolt 61 to be passed through the contact plate 49 cooperates with the threads in the opening 63 to prevent loss of the bolt 61 or removal from the contact plate 49 unless it is threaded past the threads of the opening 63.

The threaded portion 64 of the bolt 61 is arranged to engage a tapped opening 65 in the contact plate 44. At its outer end the bolt 61 has a hexagonal head 66.

It will be observed in Figure 2 that the hexagonal head 66 of the bolt 61 can be reached through the space between the switch blade members 32

and 33 above the load interrupter device 40. For this purpose, as shown in Figure 1, a hexagonal socket wrench 67 can be employed. The socket wrench 67 is mounted on an insulated live line tool handle 69. It will be apparent that the socket wrench 67 at the end of the handle 69 can be inserted in the space between the switch blade members 32 and 33 above the load interrupter device 40 for engaging the hexagonal head 66 and unscrewing the bolt 61 from the contact plate 44. This then unclamps the load interrupter device 40 and it can be withdrawn from between the switch blade members 32 and 33.

In order to permit manipulation of the load interrupter device 40 while the switch contact 35 is energized at high voltage, the terminal housing 46 is provided at its outer end with a threaded stud 70. For cooperating with the threaded stud 70 a nut 71 is secured in a socket 72 that is carried by an insulated live line tool handle 74. After the bolt 61 has been unscrewed by the wrench 67, the nut 71 can be threaded on the stud 70 and then the load interrupter 40 can be withdrawn from its position between the switch blade members 32 and 33 by suitable manipulation of the handle 74.

The load interrupter device 40 can be replaced by reversing the sequence of the steps just described. Instead of employing the threaded stud 70 and the socket 72 carrying the nut 71, conventional live line clamping devices at the end of a live line tool handle can be employed for bodily gripping the terminal housing 46 and removing or replacing the load interrupter device 40.

After the load interrupter device 40 has been replaced, the bolt 61 is tightened by means of the socket wrench 67 at the end of the insulated live line tool handle 69.

Since certain further changes can be made in the foregoing construction and different embodiments of the invention can be made without departing from the spirit and scope thereof, it is intended that all matter shown in the accompanying drawings and described hereinbefore shall be interpreted as illustrative and not in a limiting sense.

What is claimed as new is:

1. In a high voltage switch for electric power distribution circuits, in combination, a normally energizable switch contact, a movable switch blade for engaging and disengaging said switch contact for carrying load current in the engaged position, a socket member carried by and electrically connected to said switch contact and opening in the direction in which said switch blade moves to open position; an elongated load interrupter device including an insulator, and terminals at the ends of said insulator, one of said terminals having a plug formed integrally therewith for detachably interfitting with said socket member so that said load interrupter device is insertable into operative position from the front of said switch blade and can be withdrawn therefrom in the same general direction as said switch blade moves to open position; detachable locating means extending between said socket member and said one terminal for centering said load interrupter device and being capable of holding the same temporarily in plugged in position, remotely operable clamp means having a head arranged and adapted to be engaged by a socket member carried by a live line tool from a position in front of said switch blade, said clamp means extending between said socket member and said one terminal for detachably clamping the latter

in contact engagement with the former, and contact means carried by said switch blade for engaging said other terminal prior to disengagement of said switch contact by said switch blade to transfer the load current to flow entirely through said load interrupter.

2. In a high voltage switch for electric power distribution circuits, in combination, a normally energizable switch contact, a movable switch blade for engaging and disengaging said switch contact for carrying load current in the engaged position, a socket member carried by and electrically connected to said switch contact and opening in the direction in which said switch blade moves to open position; an elongated load interrupter device including an insulator, and terminals at the ends of said insulator, one of said terminals having a plug formed integrally therewith for detachably interfitting with said socket member so that said load interrupter device is insertable into operative position from the front of said switch blade and can be withdrawn therefrom in the same general direction as said switch blade moves to open position; detachable locating means extending between said socket member and said one terminal for centering said load interrupter device and being capable of holding the same temporarily in plugged in position, remotely operable clamp means having a head arranged and adapted to be engaged by a socket member carried by a live line tool from a position in front of said switch blade, said clamp means extending between said socket member and said one terminal for detachably clamping the latter in contact engagement with the former, attachment means on said load interrupter for detachably receiving a live line tool to remove said load interrupter generally in the direction in which said switch blade is moved to the open position when said clamp means is unclamped, and contact means carried by said switch blade for engaging said other terminal prior to disengagement of said switch contact by said switch blade to transfer the load current to flow entirely through said load interrupter.

3. In a high voltage switch for electric power distribution circuits, in combination, a normally energizable switch contact, a movable switch blade for engaging and disengaging said switch contact for carrying load current in the engaged position, a socket member carried by and electrically connected to said switch contact and opening in the direction in which said switch blade moves to open position; an elongated load interrupter device including an insulator, and terminals at the ends of said insulator, one of said terminals having a plug formed integrally therewith for detachably interfitting with said socket member so that said load interrupter device is insertable into operative position from the front of said switch blade and can be withdrawn therefrom in the same general direction as said switch blade moves to open position; stud means carried by said socket member and slidably engaging said one terminal for centering said load interrupter device and being capable of holding the same temporarily in plugged in position, remotely operable clamp means having a head arranged and adapted to be engaged by a socket member carried by a live line tool from a position in front of said switch blade, said clamp means extending between said socket member and said one terminal for detachably clamping the latter in contact engagement with the former, and contact means carried by said switch blade for en-

gaging said other terminal prior to disengagement of said switch contact by said switch blade to transfer the load current to flow entirely through said load interrupter.

4. In a high voltage switch for electric power distribution circuits, in combination, a normally energizable switch contact, a movable switch blade for engaging and disengaging said switch contact for carrying load current in the engaged position, a socket member carried by and electrically connected to said switch contact and opening in the direction in which said switch blade moves to open position; an elongated load interrupter device including an insulator, and terminals at the ends of said insulator, one of said terminals having a plug formed integrally therewith for detachably interfitting with said socket member so that said load interrupter device is insertable into operative position from the front of said switch blade and can be withdrawn therefrom in the same general direction as said switch blade moves to open position; detachable locating means extending between said socket member and said one terminal for centering said load interrupter device and being capable of holding the same temporarily in plugged in position, remotely operable screw clamp means having a head arranged and adapted to be engaged by a socket member carried by a live line tool from a position in front of said switch blade, said clamp means having threaded engagement with said socket member for detachably clamping said one terminal in contact engagement with said socket member, and contact means carried by said switch blade for engaging said other terminal prior to disengagement of said switch contact by said switch blade to transfer the load current to flow entirely through said load interrupter.

5. In a high voltage switch for electric power distribution circuits, in combination, a normally energizable switch contact, a movable switch blade for engaging and disengaging said switch contact for carrying load current in the engaged position, a socket member carried by and electrically connected to said switch contact and opening in the direction in which said switch blade moves to open position; an elongated load interrupter device including an insulator, and terminals at the ends of said insulator, one of said terminals having a plug formed integrally therewith for detachably interfitting with said socket member so that said load interrupter device is insertable into operative position from the front of said switch blade and can be withdrawn therefrom in the same general direction as said switch blade moves to open position; a pair of studs extending from said socket member in the direction in which said switch blade moves to open position and slidably engaging in a pair of openings in said one terminal for centering said load interrupter device, each of said studs frictionally interfitting with its respective opening so as to require a substantial force to remove said load interrupter device from operative position, remotely operable screw clamp means having a head arranged and adapted to be engaged by a socket member carried by a live line tool from a position in front of said switch blade, said clamp means having threaded engagement with said socket member for detachably clamping said one terminal in contact engagement with said socket member, and contact means carried by said switch blade for engaging said other terminal prior to disengagement of said

switch contact by said switch blade to transfer the load current to flow entirely through said load interrupter.

6. In a high voltage switch for electric power distribution circuits, in combination, support means, a normally energizable switch contact carried by said support means in insulated spaced relation, a movable switch blade pivoted on said support means in insulated spaced relation for engaging and disengaging said switch contact by swinging toward and away from said support means and for carrying load current in the engaged position, a socket member carried by and electrically connected to said switch contact and opening away from said support means and including a contact plate extending parallel to said switch blade in closed position; an elongated load interrupter device including an insulator, and terminals at the ends of said insulator, one of said terminals having a plug formed integrally therewith for detachably interfitting with said socket member so that said load interrupter is insertable into operative position from the front of said switch blade toward said support means and can be withdrawn from operative position away from said support means in the same general direction as said switch blade moves to open position and a contact plate for engaging the first mentioned contact plate flatwise; a pair of studs projecting from said first mentioned contact plate in the direction in which said switch blade moves to open position and slidably engaging a pair of openings in the second mentioned contact plate for centering said load interrupter device and being capable of holding the same temporarily in plugged in position, a remotely operable screw clamp carried by said second mentioned contact plate and having a head arranged and adapted to be engaged by a socket member carried by a live line tool from a position in front of said switch blade, said screw clamp having threaded engagement with said first mentioned contact plate for detachably clamping said contact plates in contact engagement, means mounting said screw clamp on said second mentioned contact plate so that it is freely rotatable thereon and is prevented from being readily removed therefrom, and contact means carried by said switch blade for engaging said other terminal prior to disengagement of said switch contact by said switch blade to transfer the load current to flow entirely through said load interrupter.

7. In a high voltage switch for electric power distribution circuits, in combination, a normally energizable switch contact, a pair of spaced apart switch blade members movable as a unit for engaging and disengaging said switch contact and for carrying load current in the engaged position, a socket member carried by and electrically connected to said switch contact with the socket opening thereof centrally located between said switch blade members; an elongated load interrupter device including an insulator, and terminals at the ends of said insulator, one of said terminals having a plug formed integrally therewith for detachably interfitting with said socket member whereby said load interrupter device is movable in front of said switch blade members into and out of operative position therebetween; detachable locating means extending between said socket member and said one terminal for centering said load interrupter device and being capable of holding the same temporarily in plugged in position between said

switch blade members, clamp means having a head remotely operable by a live line tool inserted from a position in front of said switch blade members and through the space therebetween and extending between said socket member and said one terminal for detachably clamping the latter in contact engagement with the former, and contact means carried by said switch blade for engaging said other terminal prior to disengagement of said switch contact by said switch blade to transfer the load current to flow entirely through said load interrupter device.

8. In a high voltage switch for electric power distribution circuits, in combination, a normally energizable switch contact, a pair of spaced apart switch blade members movable as a unit for engaging and disengaging said switch contact and for carrying load current in the engaged position, a socket member carried by and electrically connected to said switch contact with the socket opening thereof centrally located between said switch blade members; an elongated load interrupter device including an insulator, and terminals at the ends of said insulator, one of said terminals having a plug formed integrally therewith for detachably interfitting with said socket member whereby said load interrupter device is movable in front of said switch blade members into and out of operative position therebetween; detachable locating means extending between said socket member and said one terminal for centering said load interrupter device and being capable of holding the same temporarily in plugged in position between said switch blade members, clamp means having a head remotely operable by a live line tool inserted from a position in front of said switch blade members and through the space therebetween and extending between said socket member and said one terminal for detachably clamping the latter in contact engagement with the former, attachment means on the other terminal of said load interrupter device for receiving a live line tool to remove said load interrupter device in the direction in which said switch blade is moved to open position when said clamp means is unclamped, and contact means carried by said switch blade for engaging said other terminal prior to disengagement of said switch contact by said switch blade to transfer the load current to flow entirely through said load interrupter device.

9. In a high voltage switch for electric power distribution circuits, in combination, support means, a normally energizable switch contact carried by said support means in insulated spaced relation, a pair of spaced apart switch blade members pivoted as a unit on said support means in insulated spaced relation for engaging and

disengaging said switch contact and for carrying load current in the engaged position, a socket member carried by and electrically connected to said switch contact with the socket opening thereof centrally located between said switch blade members and including a contact plate extending parallel to said switch blade members in closed position; an elongated load interrupter device including an insulator, and terminals at the ends of said insulator, one of said terminals having a contact plate for engaging the first mentioned contact plate flatwise and a plug formed integrally therewith for detachably interfitting with said socket member whereby said load interrupter device is movable into and out of operative position between said switch blade members from the front thereof and on the side away from said support means; a pair of studs projecting from said first mentioned contact plate away from said support means and in the direction in which said blade members move to open position and slidably engaging in a pair of openings in the second mentioned contact plate for centering said load interrupter device and holding the same temporarily in plugged in position between said switch blade members independently of other holding means, a screw clamp having a head arranged and adapted to be engaged by a live line tool extending through the space between said switch blade members from a position in front thereof and carried by said second mentioned contact plate and having threaded engagement with an opening in said first mentioned contact plate for detachably clamping said contact plates in contact engagement, means mounting said screw clamp on said second mentioned contact plate so that it is freely rotatable thereon and is prevented from being readily removed therefrom, and contact means carried by said switch blade for engaging said other terminal prior to disengagement of said switch contact by said switch blade to transfer the load current to flow entirely through said load interrupter device.
